DESIGN FOR A BOTTLE

Fred R. High, Attleboro, Mass.

Application August 28, 1948, Serial No. 148,359

Term of patent 14 years

(Cl. D58—6)

To all whom it may concern:

Be it known that I, Fred R. High, a citizen of the United States, residing at Attleboro, in the county of Bristol and Commonwealth of Massachusetts, have invented a new, original, and ornamental Design for a Bottle, of which the following is a specification, reference being had to the accompanying drawing, forming a part thereof, and wherein Fig. 1 is a side elevational view of a bottle embodying my new design; Fig. 2 is an end elevational view of the bottle of Fig. 1 rotated 90° from the position shown in Fig. 1; and Fig. 3 is a plan view thereof.

I claim:

The ornamental design for a bottle, as shown and described.

FRED R. HIGH.
